APPARATUS FOR COLLECTING AIR MAIL
AND EXPRESS

Harry P. Trusty, Los Angeles, Calif.

Application May 21, 1934, Serial No. 726,687

7 Claims. (Cl. 258—1)

This invention relates to apparatus for collecting air mail and express into an airplane while the plane is flying. The invention is particularly useful for collecting air mail and express in a number of small cities and towns surrounding a large city, and transporting said mail and express by air to said large city for further transportation from said large city over a main airway a considerable distance to another large city or destination.

The general object of the invention is to provide an apparatus of the character stated which is simple, practical, safe and highly efficient in operation.

Other objects and advantages of the invention will appear hereinafter.

The invention is illustrated in the annexed drawings which form a part of this specification and in which,

Fig. 1 is a side elevation of my invention and an airplane on which the projection release and pick-up device is mounted, showing said airplane in position flying close to the container projecting apparatus, and said projection release and pick-up device about to engage the container bail for releasing said container projecting apparatus and picking up the container as it is projected into the air by said released container projecting apparatus.

Fig. 1 is a view like Fig. 1, except that the airplane is shown flying upwardly past the container projecting apparatus and the projection release and pick-up device, picking up the container projected from the container projecting apparatus.

Fig. 3 is a view like Fig. 2, except that the airplane is shown flying upwardly beyond its position shown in Fig. 2, and the projection release and pick-up device having swung the container up to a door in the side of the cabin of the plane, where the container is removed from said projection release and pick-up device by an attendant in the plane and delivered into the cabin of the plane.

Fig. 4 is a diagram illustrating the course and distance the container is projected by the container projecting apparatus.

Fig. 5 is a rear view of Fig. 1.

Fig. 6 is a horizontal section of the container projecting apparatus taken on line 6—6 of Fig. 8.

Fig. 7 is a vertical longitudinal section of the container projecting apparatus taken on line 7—7 of Fig. 6.

Fig. 8 is a side elevation of the container projecting apparatus.

Fig. 9 is a front end elevation of the container projecting apparatus.

Fig. 10 is a rear end elevation of the container projecting apparatus.

Fig. 11 is a side elevation of the projection release and pick-up device mounted on the side of the cabin of an airplane, a portion of the plane being shown.

Fig. 12 is a rear elevation of the projection release and pick-up device as shown in Fig. 11, a portion of the airplane being shown in cross section.

Fig. 13 is a rear side view of the outer portion of the container pick-up arm and the container hook on the outer end of said arm.

Fig. 14 is a side view of the container hook and a fragmentary vertical section of the outer end of the pick-up arm in which said hook is secured.

Fig. 15 is a vertical section of the outer end of the pick-up arm and the container hook taken on line 15—15 of Fig. 14.

Fig. 16 is a horizontal section of the outer end of the pick-up arm and the container hook taken on line 16—16 of Fig. 15.

Fig. 17 is a horizontal section of the outer end of the pick-up arm taken on line 16—16 of Fig. 15.

Fig. 18 is a rear view of the lower outer end of the pick-up arm, the container hook being removed.

Fig. 19 is a side view of the container.

Fig. 20 is a side view of the container taken at right angles to Fig. 19.

Corresponding parts are designated by the same reference characters in all the figures of the drawings.

My invention comprises generally a projecting apparatus 1, mounted on the ground or on a building or other structure, and a projection release and pick-up device 2, mounted on an airplane 3, for releasing a mail and express container 4 from said projecting apparatus and picking up said container, as it is projected by said projecting apparatus, and delivering said container into said airplane while flying, as will be hereinafter more fully described.

Said projecting apparatus includes a projector cage 5, a spring-projecting plunger 6, and a trigger-mechanism 7 for holding the container 4 in said cage against said plunger and said plunger in retracted position, until said container and plunger are released by the engagement of said release and pick-up apparatus with said trigger mechanism, as will be hereinafter more fully described.

The projector cage 5 is mounted upon a sup.

porting frame 8 and comprises a head 9 at its rear end, a plurality of bands 10 spaced forwardly of said head and a plurality of angle irons 11 extending longitudinally of and spaced around 5 the outside of the cage and secured to said head and said bands. The cage 5, container 4 and plunger 6 are preferably rectangular in cross section and roller bearings 12 are provided within said cage, two of which bearings being 10 secured to the head 9 and bands 10 at the sides of the cage 5, two at the bottom and two at the top of said cage, on which bearings the container 4 and plunger 6 are mounted to slide in the cage and are thereby prevented from jamming 15 in the cage, when the container is projected, by said spring projecting plunger, forwardly out of said cage.

The plunger 6 is hollow and closed at its forward end by a head wall 13, to which wall are secured the forward ends of five plunger rods 14, 20 15, 16, 17 and 18, which extend rearwardly through said plunger and through slide bearings 19, 20, 21, 22 and 23, respectively, in the cage head 9; the rod 14 being solid and secured 25 to the plunger head wall 13 centrally of the plunger 6, and the plunger rods 15, 16, 17 and 18 being tubular and secured to the plunger head wall 13 about said center rod 14 with the rods 15 and 16 above and at opposite sides respectively 30 of said center rod, and the rods 17 and 18 below and at opposite sides respectively of said center rod. Expansion coil springs 24, 25, 26, 27, and 28 surround the plunger rods 14, 15, 16, 17, and 18 respectively within the projection cage 35 5 and the plunger 6 and bear at their ends respectively against the cage head 9 and the plunger head wall 13, which springs are compressed when the plunger is retracted and expand to project the plunger 6 forwardly and the container 4 out of the projector cage 5 in the manner hereinafter more fully described.

The rear ends of the plunger rods 14, 15, 16, 45 17 and 18 extend through a plate 29 and said plate is held on the rear threaded ends of said rods by nuts 30, 31, 32, 33 and 34 which screw on said threaded ends of said rods respectively against the rear side of said plate. Shock absorbing coil springs 36 surround the rear portions of the plunger rods 15, 16, 17 and 18 respectively, bearing at their rear ends against the plate 29 and at their forward ends against collars 37 on said rods respectively, which collars are secured to the forward ends of rubber sleeves 38 which enclose said springs 36 and are secured 55 at their rear ends to said plate.

The central plunger rod 14 is formed with a rack 40 on its lower side in mesh with a pinion 41 secured on a crank shaft 42 extending transversely of the head 9 of the projector cage 5 and slidably journaled in bearings 43 and 44 on said head, there being a ratchet wheel 45 secured on said crank shaft which is engaged by a pawl 46 pivoted on bearing 44 on the cage head 9, and a crank 47 is secured on one end of said crank shaft 42 for rotating the same.

The trigger mechanism 7 includes a trigger 50, a trigger release lever 51 and a bail 52 pivotally connected to the forward or upper end of the container 4. Said bail comprises a pair of spaced 60 side arms 53 bent rearwardly intermediate their ends, an upper cross rod 54 connecting the upper ends of said arms and a lower cross rod 55 connected to the bent portion of said side arms below said upper cross rod, the lower ends of said side arms being pivoted at 56 to connecting

arms 57 secured to the sides respectively of the container 4 and extending beyond the forward end or above the upper end of said container. The trigger 50 is mounted to slide vertically in 5 a pair of spaced lugs 58 and 59 projecting rearwardly from the head 9 of the projector cage 5, and a spring 60 surrounds said trigger, bearing at its upper end against the upper lug 58 and at its lower end against a pin 61 extending through the trigger, for projecting the lower end of the 10 trigger into a notch 62 in the upper side of the central plunger rod 14 for holding the plunger 6 retracted against the tension of the springs 24, 25, 26, 27 and 28, as shown in Figs. 6, 7 and 8 of the drawings. The upper end 63 of the 15 trigger 50 is bent forwardly at right angles to the trigger for overlapping and engaging the rear end of the trigger release lever and holding the forward end 64 of said lever, which end is bent upwardly at a slight angle, under and 20 against the lower cross rod 55 of the container bail 52, whereby the container 4 is held within the projector cage 5 against the retracted plunger 6 and the bail 52 is held in position to be engaged by the release and pick-up apparatus 25 on the airplane 3 for releasing the trigger 50 from the notch 62 in the plunger rod 14 and for picking up the container 4 as it is projected forwardly from the projector cage 5 by the springs 24, 25, 26, 27 and 28, as will be hereinafter more 30 fully described.

The container 4 may be constructed in any suitable manner of light fireproof material and the forward or upper end thereof is closed by a removable cover 65 which is detachably held in 35 closed position by slide bolts 66 mounted thereon which engage openings 67 in the bail connecting arms 57 on the forward or upper end of the container.

The projecting apparatus 7 is covered by an 40 inverted rounded U-shaped hood 70 which extends downwardly from the rear end of the projector cage 5 and the sides thereof slope outwardly in a downward direction, which hood protects the projecting apparatus from the release and 45 pick-up apparatus should the plane fly too low.

The projecting apparatus 7 is mounted on a table 71 which stands on the ground at a suitable location and said apparatus may be inclined upwardly in a forward direction at any suitable 50 angle by placing a block 72 of suitable thickness on the top of the table under the forward end of the base 73 of the cage supporting frame 8 with the rear end of said base resting directly upon said table top, as shown in Figs. 1 and 2.

The projection release and pick-up device 2 comprises a U-shaped brace member 75, a pick-up arm 76, a container hook 77 on the outer end of said arm, a cable 78 connected to said arm and an automatic cable winding device, such as 60 a trolley retriever 79.

The ends of the U-shaped brace member 75 are pivoted to one side of the fuselage 80 of the airplane 3 at opposite sides respectively of a door 81 in the corresponding side of the cabin 82 of the 65 plane, as at 83. One end portion 84 of the pick-up arm 76 is bent at right angles to the arm and is pivoted at 85 to the under side of the fuselage 80 near the side thereof to which the ends of the brace member 75 are pivoted, so that when the 70 arm 76 is swung down on its pivot 85 for picking up a container 4, it will rest a suitable distance below the fuselage. The brace member 75 is formed with a sleeve 86 on its swinging end portion, through which sleeve the pick-up arm 76 75

extends and slides. The pick-up arm 76 is formed in two sections 87 and 88, the section 87 being tubular and being the section that is pivoted at 85 to the fuselage 80 of the plane, and the section 88 extending into the outer end of said tubular section and telescoping in said section, there being a coil spring 87' mounted in the outer end of the section 87 which spring engages the inner end of the section 88. A removable pin 89 extends through openings 90 in the section 87 and through a longitudinal slot 91 in the section 88 of the pick-up arm 76, to prevent the section 88 from turning in the section 87, when the hook 77 engages the container bail 52 for releasing the container 4 from the container projecting apparatus 1 and picking up the container as it is projected from said apparatus, the hook 77 being secured in the outer end 92 of the section 88 of the pick-up arm 76, which end 92 is bent downwardly from said section. Said downwardly bent end 92 is provided with a recess 93 extending upwardly from its lower end and through its rear side to receive the hook shank 94 which extends upwardly from the hook 77, said bent end 92 being formed with inturned flanges 95 extending inwardly from the sides respectively of the recess 93 at the lower end thereof, which flanges engage grooves 96 respectively in opposite sides of the hook shank 94, when said shank is introduced into the recess 93 from the rear of said bent end 92 of the section 88 of the pick-up arm 76, whereby the hook 77 is detachably connected to said bent end. The bent end 92 of the arm section 88 is provided with small transverse holes 97 and the hook shank 94 is provided with a corresponding hole 98, through which hole a small pin 99 is driven for securing the hook shank in the recess 93 in the lower end of said bent end 92. A flat spring 100 is secured at its upper end to the forward side of the shank 94 of the hook 77 and extends downwardly across the hook behind a shoulder 101 on the upper side and at the rear of the point 102 of the hook.

The cable winding device 79 is mounted in the cabin 82 of the airplane 3 at the side of the cabin door 81 adjacent the pick-up arm 76, and the cable 78 is secured at one end to the drum of said winding device and extends upwardly in the cabin over a pulley 103 in the upper part of the cabin and out through the side of the cabin downwardly under a pulley 104 mounted on the outer end of section 87 of the pick-up arm 76, and the outer end of said cable is secured to the outer portion of the section 88 of said pick-up arm at 105. A handle 106 is provided on the winding device 79 for rotating the drum of the device to unwind the cable 78 therefrom or to wind up the cable on said drum if desirable.

The operation of my invention is as follows: The plunger 6 being in its projected position, under the influence of springs 24, 25, 26, 27 and 28, after it has projected a container 4 from the cage 5, and said container has been picked up by the projection release and pick-up device 2 and delivered into the airplane 3, the crank shaft 42 is shifted in its bearings until the pinion 41 meshes with the rack 40 in the lower side of the plunger rod 14, and the pawl 46 engages the ratchet wheel 45. The crank shaft 42 is then rotated clockwise by the crank 42; whereby the pinion 41 is likewise rotated in mesh with the rack 40, and the plunger 6 is drawn rearwardly in the cage 5 by the plunger rod 14, against the tension of the springs 24, 25, 26, 27 and 28, until said plunger is retracted to its initial projecting position and said springs are

compressed for projecting said plunger forwardly, as illustrated in Figs. 6 and 7 of the drawings, in which position of the plunger the trigger notch 62 in the upper side of the plunger rod 14 is brought under the trigger 50, whereupon the trigger spring 60 projects said trigger downwardly and its lower end into engagement with said notch, and said plunger and springs are held in their retracted position for projecting a container 4 from the cage 5, as illustrated in Figs. 7 and 8 of the drawings. The crank shaft 42 is then shifted until the pinion 41 disengages the rack 40. A bag of mail or a load of express is placed in a container 4 and the cover 65 placed over the open end of the container and secured in such position by the engagement of the slide bolts 66 with the openings 67 in the container bail connecting arms 51. Said container is then placed in the cage 5 with its rear end against the plunger 6 and its forward end projecting slightly beyond the forward end of said cage. The container bail 52 is then swung upwardly on its pivots 56 over the forward upwardly bent end 64 of the trigger release lever 51, with the lower cross rod 55 of the bail engaging the upper side of said bent end and holding said lever 51 in position with its rear end against the under side of the upper bent end 63 of the trigger 50, as illustrated in Figs. 1, 7 and 8 of the drawings. The container projecting apparatus 1 is now set for projecting the container 4 from the cage 5, when said apparatus is released by the projection release and pick-up device 2 on the airplane 3, in the manner as will now be described.

The projection release and pick-up device 2 on the airplane 3 is then set for releasing the container projecting apparatus and picking up the container 4 as it is projected by and from said apparatus, by swinging down the pick-up arm 76 and brace member 75 on their pivots 85 and 83 respectively into their position shown in full lines in Figs. 1 and 12 of the drawings, in which position the pick-up arm 76 rests in a horizontal position projecting from one side and a short distance below the plane with the arm section 88 projected forwardly from the arm section 87 by the spring 87', the cable winding device 79 allowing the cable 78 to unwind therefrom to allow said pick-up arm and brace member to swing down into such position.

The pilot of the airplane 3 flies the plane down to an altitude slightly above the hood 70, and forwardly at a predetermined speed, for example, one hundred fifteen miles per hour, on a course that will bring the hook 77, on the outer end of the section 88 of the pick-up arm 76, directly over and close to said hood, so that the point 102 of said hook will pass under the upper cross rod 54 of the container bail 52, until said cross rod, escaping the hook spring 100, passes into the hook and is engaged by the rear portion of said hook, whereupon the bail 52 is swung forwardly on its pivots and the lower cross rod 55 of the bail, engaging the forward upwardly inclined forward end 64 of the trigger release lever 51, cams said end of said lever downwardly and the rear end of said lever upwardly, whereby said rear end of said lever, engaging the upper forwardly bent end 63 of the trigger 50 lifts said trigger upwardly and its lower end out of the notch 62 in the plunger rod 14, releasing said rod and the plunger 6, whereupon the five springs 24, 25, 26, 27 and 28 expand with great force and project the plunger 6 forwardly and the plunger, engaging the rear end of the container 4, projects said container forwardly out of the forward end of the cage 5

at a rate of speed corresponding to the rate of speed of the airplane and at an upward inclination, for example thirty-five degrees (35°), corresponding to the inclination at which the pilot flies the plane upwardly as the hook 77 engages the container bail 52, thus hooking the container on the outer end of the arm 76 of the projection release and pick-up device 2. As the container leaves the cage 5 and the hook 77 suddenly receives the weight of the container 4, a sudden downward pull is applied by the container to the outer end of the pick-up arm 76 and to the cable 78 and drum of the cable winding device 79, whereupon said device is actuated to enable its mechanism to rotate said drum to wind up the cable 78 thereon, which swings the pick-up arm 76 and brace member 75 upwardly on their pivots 85 and 83, respectively, into a vertical position adjacent the outside of the cabin 82 of the plane 3, and thereby elevates the container to a position opposite the cabin door 81, during which operation the weight of the container on the hook 77 draws the arm section 88 downwardly against the tension of the spring 87' into the upper end 25 of the section 87 of the pick-up arm 76, until the bent end 92 of said arm section 88 rests adjacent the upper end of said arm section 87, thus cushioning the container on the pick-up arm during its upward movement and bringing the container and hook 77 into a convenient position where the container bail 52 may be readily removed by an attendant from said hook and the container delivered by the attendant through the door 81 into the cabin 82 of the airplane 3, as illustrated in Figs. 3, 11 and 12 of the drawings.

As the plunger 6 of the container projecting apparatus is projected forwardly by the expansion of the five springs 24, 25, 26, 27 and 28, and the container 4 projected by said plunger forwardly out of the cage 5, the forward movement of said plunger is limited by the engagement of the spring-pressed collars 31, on the plunger rods 15, 16, 17 and 18, with the plunger rod bearings 20, 21, 22 and 23 on the cage head 9, and the shock of such engagement of said collars with said bearings is absorbed by the shock absorbing springs 36 on the rear ends of the plunger rods 15, 16, 17 and 18.

Should the container projecting apparatus 1 fail to function and project the container 4 from the cage 5, when the hook 77 of the projection release and pick-up device 2 engages the upper cross rod 54 of the container bail 52, the light pin 99 will be sheared, at the adjacent faces of the hook shank 94 and the recess 93 in the lower end 55 of the section 88 of the pick-up arm of said release and pick-up device 2, by the forward pressure of said pick-up arm and the resistance of said bail cross rod 54, as the airplane 3 continues forwardly, and the lower end of said pick-up arm 60 will escape the hook 77, the shank 94 of which hook passing out of the rear open side of said recess 93 and the flanges 95 in the lower end of the pick-up arm section 88 sliding forwardly out of the shank grooves 96, leaving the hook on said 65 bail cross rod, thus preventing serious damage to the container projecting apparatus 1 or the container release and pick-up device 2.

In this specification and the annexed drawings I disclose my invention in a form which I consider desirable, but I do not limit my invention to such form, because it may be embodied in other forms, and it is to be understood that in the claims of this specification I intend to cover my invention in whatever form it may be embodied.

75 I claim as my invention:

1. A container projecting apparatus comprising a cage in which a container is placed to be projected, a plunger slidably mounted in said cage and against which said container is placed, springs in said container engaging said plunger for projecting the same forwardly in said cage and causing said plunger to project said container from said cage, a plunger rod, a rack on said plunger rod, a crank shaft journaled on said cage, a pinion on said crank shaft in mesh with 10 said rack for retracting said plunger against the tension of said springs when said crank shaft is rotated in one direction, said plunger rod being provided with a notch, and a trigger for engaging said notch and holding said plunger retracted until 15 said trigger is released from said notch.

2. A container projecting apparatus as characterized by claim 1 including a bail pivotally connected to the forward end of said container, and a trigger release lever pivoted to said cage and 20 formed with an inclined end to be engaged by a part of said bail for holding the other end of said lever against a part on said trigger and for swinging said lever, when said bail is swung on its pivots, for disengaging said trigger from said 25 notch to release said plunger rod and said plunger.

3. A pick-up device comprising a pick-up arm pivoted to an airplane to be swung out from the plane into a position for picking up an object, 30 said arm comprising two telescopic sections, one of said sections being pivoted to the airplane, a pick-up hook on the outer end of the other section, a spring in said pivoted section against which bears the inner end of said hook section, 35 and means for swinging said arm and an object hooked thereon upwardly adjacent the plane.

4. A pick-up device comprising a pick-up arm pivoted to an airplane to be swung out from the plane into position for picking up an object, a 40 pick-up hook slidably mounted on the outer end of said arm, a pin for normally holding said pick-up hook in said arm for picking up the object when the plane flies near said object, and said pin being of such strength as to break and allow 45 said pick-up hook to slide out of said arm in case said object resists being picked up beyond a predetermined pressure.

5. A pick-up device comprising a pick-up arm pivoted to an airplane to be swung out from the 50 plane into position for picking up an object, means for swinging said arm and an object picked up thereby upwardly adjacent the plane, and a brace member pivoted to the plane and in which said arm is slidably mounted for swinging up or 55 down with said pick-up arm and for bracing said pick-up arm.

6. A container projecting apparatus comprising a cage in which a container is placed to be projected, a plunger slidably mounted in said cage 60 and against which said container is placed for projection, a plunger rod provided with a notch, a trigger for engaging said notch and holding said plunger retracted until said trigger is released from said notch, a bail pivotally connected to 65 the forward end of said container, and a trigger release lever pivoted to said cage and formed with an inclined end to be engaged by a part of said bail for holding the other end of said lever against a part on said trigger and for swinging said lever, 70 when said bail is swung on its pivots, for disengaging said trigger from said notch to release said plunger rod and said plunger, and means for projecting said plunger forwardly in said cage and causing it to project said container from said 75 cage.

cage when said plunger is released by the disengagement of said trigger from said notch.

7. In combination, a container projecting apparatus, a container to be projected by said container projecting apparatus, a hood fitted over said projecting apparatus and inclined upwardly to the discharge end of said projecting apparatus, an engageable member connected to the forward end of said container to be swung upwardly above the forward end of said hood when said container is positioned in said projecting apparatus to be projected, releasing means to be actuated by said

engageable member, a pick-up arm pivoted to an airplane to be swung downwardly and outwardly from the plane into position to engage said engageable member to actuate said releasing means to enable said projecting apparatus to project said container, and to pick up said container as it is projected by said projecting apparatus, and means for swinging said arm and the container picked up by said arm upwardly alongside said airplane. 5

HARRY P. TRUSTY.

10
